UNITED STATES PATENT OFFICE.

ALEXANDRE MARIE JOSEPH NOVELLA, OF GRENOBLE, FRANCE.

SAFETY-HOOK.

SPECIFICATION forming part of Letters Patent No. 712,085, dated October 28, 1902.

Application filed May 24, 1901. Serial No. 61,772. (No model.)

To all whom it may concern:

Be it known that I, ALEXANDRE MARIE JOSEPH NOVELLA, a citizen of the French Republic, residing at Grenoble, Isère, France, ⁵ have invented a certain new and useful Improved Safety-Hook, of which the following is a specification.

My invention relates to an improved safety-hook adapted for tethering or coupling animals and for other purposes, the object being ¹⁰ to provide a simple device which can expeditiously be engaged with the part desired.

My invention is illustrated in the accompanying drawings, in which—

¹⁵ Figure 1 is a side view of the hook, the ring being in section. Fig. 2 is a front view. Fig. 3 shows the position adopted by the parts in the operation of attaching a tether coupling-strap, bridle, or the like to the hook. Fig. 4 ²⁰ represents the hook with the strap attached thereto. Fig. 5 shows the movable tongue and ring of the hook before being bent into position around the supporting-staple or the like.

²⁵ The improved device consists of a hook or curved tongue *a*, which is movable and is suspended by an eye *a'* from a staple *b*, which may be embedded in a wall or fastened to any suitable support. The eye *a'* is preferably ³⁰ formed as shown in Fig. 5 and bent to shape around the staple. The tongue *a* is provided with a hole *a²* below the eye *a'*, in which hole is loosely suspended a ring *c* of less diameter than the distance between the hole and the ³⁵ free end *a⁴* of the tongue, so that in the normal position of the parts the ring rests against the under side of the tongue *a* at a point *a³*, and the tongue or hook cannot at any time pass through said ring.

⁴⁰ The manner of using the safety-hook for securing a bridle, for example, is as follows: The movable hook is first raised vertically, as shown in Fig. 3, and after lifting the ring *c* into a nearly horizontal position the loop

formed by the bridle is passed through the ⁴⁵ ring from below upward and moved in the direction *z*, so as to pass over the end *a⁴* of the tongue. All that is then necessary is to release the whole, which thereupon takes up the position shown in Fig. 4. It is then evi- ⁵⁰ dently impossible for the bridle to become detached from the hook either by the efforts of the tethered animal or from any other cause unless the release is effected by an intelligent being. To unloose the bridle from the hook, ⁵⁵ it is sufficient to take hold of the part *x* of the bridle, draw the same forward, slightly raise the hook, and pass the said part *x* of the bridle under the hook. The bridle being then released will naturally escape from the ⁶⁰ ring. The same course is followed when it is desired to fasten to the hook the end link of a chain.

From these particulars the different uses to which the improved device can be applied ⁶⁵ will be readily apparent. It may, for example, be used for tethering animals by the aid of cords, bridles, or chains and will afford a convenient and reliable means for supporting wires, cables, and the like, as well as serving ⁷⁰ as a coupling-hook for harness.

What I claim is—

The combination with the staple and the curved tongue pivotally suspended at its upper end therefrom, of the ring loosely connected to the tongue below said upper end and of less diameter than the distance to its free end, whereby the curved portion of the tongue will normally extend rearwardly through the ring and engage the lower side ⁷⁵ ⁸⁰ thereof, substantially as set forth.

In testimony whereof I have hereunto set my hand in the presence of two subscribing witnesses.

ALEXANDRE MARIE JOSEPH NOVELLA.
